(57) **CLAIM**

I claim the ornamental design for a dimple for a golf ball, as shown and described.

DESCRIPTION

FIG. 1 is a front elevational view of a dimple for a golf ball embodying my new design;

FIG. 2 is an enlarged front elevational view of the dimple of FIG. 1;

FIG. 3 is an enlarged front elevational view of the dimple of FIG. 1 used to reference various cross-sectional views of the dimple of FIG. 1;

FIG. 4 is a cross-sectional view of the dimple of FIG. 3 taken along section line 4—4 of FIG. 3;

FIG. 5 is a cross-sectional view of the dimple of FIG. 3 taken along section line 5—5 of FIG. 3; and,

FIG. 6 is a partial cross-sectional view of the dimple of FIG. 3 taken along section line 6—6 of FIG. 3.

In FIG. 2, the broken line, shown immediately adjacent and around the solid lines of the dimple, forms an unclaimed boundary of the design. The broken lines outside the unclaimed boundary in FIG. 1 are included for the purpose of illustrating the environment of the dimple; and form no part of the claimed design.
